UNITED STATES PATENT OFFICE.

EDGAR L. LOGEE, OF PROVIDENCE, RHODE ISLAND.

DESIGN FOR A BADGE.

SPECIFICATION forming part of Design No. 34,522, dated May 21, 1901.

Application filed April 11, 1901. Serial No. 55,429. Term of patent 7 years.

To all whom it may concern:

Be it known that I, EDGAR L. LOGEE, a citizen of the United States, residing at Providence, in the county of Providence, in the 5 State of Rhode Island, have invented and produced a certain new and useful Design for a Badge; and I declare the following to be a specification thereof, reference being had to the accompanying drawings, forming a part 10 hereof.

Figure 1 is a plan view of the badge. Fig. 2 is a side elevation of the same.

As shown in the drawings, the leading and material features of my design consist of an 15 inverted crescent having a marginal band thereon on both the larger and smaller curve; a spread eagle, whose head extends up on the marginal band of the inner curve of said crescent at the center of said band and whose 20 wings are stretched so that their tips just cover the marginal band of the outer curve of said crescent at two points; a shield having a marginal band around it, on the top of which shield the feet of the eagle are represented 25 as resting, said shield having an upper hori-

zontal blue field showing stars thereon and its lower portion divided into alternate white and red bars of equal width; an S-shaped scroll or ribbon on each side of the feet of the eagle and apparently extending from behind 30 said feet to the sides of the badge and covering the points of the crescent and having its ends shown as returned inwardly behind the crescent toward the wings of the eagle, and two olive-leaves extending angularly down- 35 ward on the two opposite sides of the shield, between said shield and ribbon or scroll.

Having thus described my invention, what I claim as new, and desire to secure by Letters Patent, is—

The design for a badge as herein shown and described.

In testimony whereof I have signed my name to this specification in the presence of two subscribing witnesses.

EDGAR L. LOGEE.
